ELECTRIC CONTROL DEVICE AND ELECTROLYTIC FLUID THEREFOR

Charles H. Ray, Alameda, and Joseph N. Sears, Sacramento, Calif., assignors to Lindberg Instrument Co., Berkeley, Calif., a corporation of California

Application July 31, 1951, Serial No. 239,532

8 Claims. (Cl. 201—57)

1

This invention relates to an improved electric control device of the type employing a liquid current-modulating medium. Such a control device may be used in a phonograph pickup or in a microphone or in any other instrument that is used to modulate electric current in accordance with mechanical motion, sound vibrations, and the like.

In the type of electric control device to which this invention relates, two or more chambers, each containing an electrode and a liquid that will conduct electricity, are connected by one or more variable-area orifices. An electrical potential is impressed between the electrode in one chamber and the electrode in another chamber. Then when external forces vary the area of the orifice between them, the total electrical resistance to the electrical current flowing through the orifice is similarly varied. By this means a signal set up by external mechanical forces can be faithfully reproduced electrically with corresponding frequency and amplitude characteristics. For example, a phonograph needle following a record groove may be connected rigidly to an actuator arm having means to vary the area of the orifice and thereby set up voltage variations corresponding in frequency and amplitude characteristics to the record groove. This voltage may be transmitted, amplified, and used to control the sound energy of a loud speaker, giving a faithful reproduction of the original recording. The present invention solves certain problems that have occurred in such control devices.

One problem has been the building up of gas inside the electrode chambers. These chambers are usually sealed off by a flexible rubber diaphragm which overlies a trough or gap in the wall between two adjacent chambers and cooperates with the partition and the gap to form a variable-area orifice. In the past, gas has built up inside the chambers and has distended and bulged the diaphragm. This bulging has, in itself, disturbed the response of the device. In some cases enough gas has built up to break the diaphragm loose from the chamber wall so the liquid has spilled or has been exposed so it can evaporate freely. The present invention has solved this problem by a novel combination of elements that prevents gas from forming to any harmful extent.

Another related problem has been the tendency of the liquid to evaporate through the pores of the rubber diaphragm. When evaporation reduced the volume of the liquid, the diaphragm would be caused to lay in the trough or gap to 55

such an extent as to cut off the current flow through the gap. The present invention solves this problem by providing a liquid medium that does not readily evaporate.

5 Another problem has been the building up of excessive ionization in one chamber and a deficiency of ions in another chamber. This has occurred because the orifices between chambers have preferably been kept small, in order to get 10 greater output from less mechanical actuation of the diaphragm. The result of uneven ionization has been a severe reduction of output, due to a large increase in resistance in the negative (cathode) cell. In phonographs this has tended to reduce the volume to a uselessly small amount.

A further problem has been the formation of oxides and other undesirable coating on the anode. These coatings have acted as electrical insulators and have tended to cut down the current flow. In many cases the entire anode has become covered with this insulating coating, and the current flow has ceased altogether.

The two last named problems have been solved by a novel combination of electrodes, electrolyte, and liquid medium and by an initial concentration of the ionizing agent in the cathode chamber far in excess of the concentration in the anode chamber.

Still another problem solved by the invention has been the production of a unit having a relatively long and predictable life, which may be substantially co-extensive with the life of the needle, so that the greatest advantage may be taken of needles having a long life. The invention makes feasible the permanent mounting of the needle in the cartridge instead of having to provide a socket, set screw, etc., to receive the needle. This means that the mass of the actuating arm of the pickup can be reduced to a minimum, thereby insuring maximum tracking ability and minimum distortion. It also prevents tampering, so that no one can change the orientation of the needle and thereby damage the records and shorten the useful life of the needle.

A further problem solved by the invention is the protection of the rubber diaphragms from harmful chemical action by the electrodes.

Still other objects and advantages of the invention will become apparent from the following description of a preferred embodiment, which will be discussed in connection with a phonographic pickup that exemplifies a control device employing the invention. The invention is not, however, limited to such use, nor to the other specific features that are given by way of example in order

to comply with the statute. The scope of the invention is defined by the appended claims.

In the drawings:

Fig. 1 is an enlarged isometric view of a photographic pickup cartridge embodying the principles of the invention.

Fig. 2 is an isometric view similar to Fig. 1 showing the cartridge with the upper protective cover removed.

Fig. 3 is an enlarged isometric view partly in section taken generally on the line 3-3 of Fig. 2 with some portions cut away to show the needle mounted on the front end of the actuator arm.

Fig. 4 is an isometric view similar to Fig. 2 of the body member of the cartridge, with the diaphragm and the actuator arm removed to show the chambers and the electrodes and the liquid therein.

Fig. 5 is a view in elevation and in section taken along the line 5-5 of Figs. 2 and 4.

Fig. 6 is a view in perspective of one of the outer electrodes; and

Fig. 7 is a view in perspective of the center electrode.

The invention will be better understood from a specific example, and for this reason a photograph pickup employing the invention will first be briefly described, with reference to the drawings. Fig. 1 shows a pickup 10 having a body member 11 and a protective cover member 12, both made from an electrical insulating material, such as a moldable plastic. The body member 11 is recessed (see Figs. 4 and 5) to provide three cavities or chambers 13, 14 and 15, separated from each other by suitable partitions 16, 17 and 18. The partitions 17 and 18 are each formed with a small gap-like depression or trough 20, 21 which extends generally at right angles to the partition. The gap 20 extends between the chambers 13 and 14 and the gap 21 extends between the chambers 14 and 15. All the electricity passing from one chamber to another must be conducted by the liquid lying in these shallow connecting troughs.

Each chamber 13, 14, 15 has an electrode 22, 23, 24 respectively, and a terminal 25, 26, 27 respectively extending outside the body 11. The present invention is best practiced when the shape, size, and composition of these electrodes bear a certain relation, and these features will be discussed below. The invention also involves the electrolytic fluid 30 which is used to fill the three chambers 13, 14, 15 and to lay in the gaps 20, 21. Its composition and disposition are discussed below.

After the three chambers (there may be two or more) have been filled with the fluid 30, they are covered with a rubber diaphragm 31 (Figs. 2 and 5), which is cemented to the body 11 and to its partitions so as to seal the fluid 30 in the chambers. A longitudinally extending actuator arm 32 (see Figs. 2 and 3) is mounted on suitable bearing blocks 33 and 34 (see Fig. 4) so as to move normal to its longitudinal axis through a small arc in response to the lateral movement of a needle 35 secured in a chuck 36 at the lower end of the arm 32 (see Fig. 3). When the needle 35 is moved back and forth as it traverses the record groove, a pair of side lever or presser foot members 37 and 38 (Figs. 2 and 5) extending outwardly from the actuator arm 32 each alternately press down and let up on the diaphragm 31 over the gaps 20 and 21, so that the area of the gap orifices formed by the diaphragm and the gaps is contracted or enlarged in response to the needle movement. Then when the needle 35 ro-

tates the actuator arm 32 (Fig. 5) in a clockwise direction the lever 37 will rise so the orifice at the gap 20 will be enlarged while the lever 38 will fall so the orifice at the gap 21 will be reduced in size. When the needle 35 swings the arm 32 in the counter-clockwise direction the opposite effect is obtained.

When an electric potential is impressed across the terminals 25 and 27, the electric current passes between the electrodes 22 and 24 by way of the orifices above the gaps 20 and 21, and the variation in orifice size produces a corresponding variation in the voltage of the center electrode 23. This voltage signal may be drawn off from the terminal 26, amplified, and converted to sound having the frequency and amplitude characteristics of the record groove. The many advantages of the three chamber structure have already been set forth in pending application, Serial No. 239,531, filed July 31, 1951.

The present invention concerns certain discoveries of the advantages to be obtained from a new relationship between the electrodes 22, 23, 24, the chambers 13, 14, 15, and the fluid 30. It concerns electrodes made from a metal more noble than hydrogen in the electromotive series, so that the electrodes will not liberate gas from the liquid. It concerns as the electrolyte a solution of a salt or other ionizable compound of metal from the same group as the metal in the electrode. It concerns as the liquid medium in which the salt is dissolved a mixture of water and a hygroscopic fluid, in a proportion where the hygroscopicity exactly balances the evaporative tendency of the water. In addition, the combination includes the use in dilute form of an acid of a type which will react with the coating that tends to form on the electrodes and will produce a soluble product, the acid being of a type that ionizes in water to form a hydrogen or hydronium ion. The individual elements of the combination and their disposition in the device will now be discussed in detail.

The electrode metal

In order to help prevent the formation of gas in the sealed chambers 13, 14 and 15, the electrodes are made from a metal standing higher than hydrogen in the electromotive series. Such metals as copper, silver, polonium, tellurium, mercury, palladium, platinum, and gold answer this qualification. Mercury could be used but being a liquid at room temperatures and forming very toxic salts, is generally unsatisfactory for use around humans. Also some lead ions and some non-metallic ions which stand higher than hydrogen in the electromotive series, but as to these lead cannot be used because it also has ions lower than hydrogen in the series and therefore liberates hydrogen and oxygen from water, and the non metals cannot be used as electrodes because they are non-conductors. Copper and silver give very satisfactory results and are relatively inexpensive. Alloys of two or more metals from the usable metals in the above-defined group may be employed if the gradual dissolution of the anode will not change the characteristics of the electrolyte.

The selection of the metal for the electrode is affected by the selection of the electrolyte and the foundation liquid, because when an electric current is applied, the anode will gradually dissolve, forming a salt. In order to maintain the electrolyte with the same response characteristics, the salt formed must be soluble in the foundation

liquid and must have substantially the same characteristics as the chosen electrolyte.

The electrodes

The outer electrode 22 which serves as the anode is gradually eaten away as the device operates, losing metal to the electrolytic solution. At the same time, the other electrode 24 which serves as the cathode accumulates metal, as it removes the metallic ions from the solution. The center electrode 23 remains substantially unaffected. For that reason it may be made substantially smaller than the other electrodes (see Fig. 7). Preferably the center electrode is supported near the upper level of the fluid 30, by a support member 40, which may be an integral part of the body 11.

The outer electrodes 22, 24 are preferably bar shaped as shown in Fig. 6, to extend from the bottom of their chambers 13, 15 almost to the top, and with a rectangular section, exposing a large surface area. Their size helps determine the life of the control device, and in a phonograph pickup is preferably calculated to give an electrode life of about twice the normally expected life of the needle.

Some metals, such as copper, if used for the electrode, would adversely affect the rubber of the diaphragm upon prolonged contact with it. As a protection, this invention includes a cover member 41, 42 over each electrode 22, 24 (Figs. 4 and 5), made from the same plastic as the body 11 or from any other suitable insulating material.

The liquid

Water is an essential component of the liquid in order that there be ionization of the electrolyte. The main trouble with pure water is its tendency to evaporate, even through a rubber diaphragm. When it evaporates, the liquid level drops, and electrical conduction through the ori-

5

45
50

Pure hygroscopic liquids, even if they would work electrically, would be undesirable, because they gradually pull water out of the air, even through the rubber diaphragm. This additional water will lift the diaphragm away from the partitions and the device will fail to operate.

The present invention uses a mixture of water with a hygroscopic liquid, in such proportions that its attraction of water balances the tendency of the water to evaporate. The liquid level then remains substantially constant.

The hygroscopic fluid to be used must be freely miscible with water and must not cause precipitation of salts from the electrolytic solution used. Among satisfactory liquids are a number of glycols, diols, glycol ethers, and amines.

Such glycols, for example, as ethylene glycol, diethylene glycol, triethylene glycol, propylene glycol and dipropylene glycol are satisfactory. As an example of a balanced solution, a mixture of about 23% water with approximately 77% ethylene glycol has proven satisfactory.

Among the satisfactory diols are pentanediol-2, 4, 2-ethylhexanediol-1, 3, and 2-methylpentane-diol-2, 4.

Among the satisfactory amines are diethylamine, isopropylamine, ethylenediamine, diethyletriamine, triethylenetetraamine, and triethanolamine.

To prevent the formation of an oxide coating on the electrode, a small trace of acid may be added to the above liquid. For example, with copper electrodes, the addition of about one percent of sulfuric acid to 99% glycol-water mixture has proven satisfactory. Other acids, such as

nitric acid, that attack such coatings may be used, and no gas will be formed thereby, provided the acid liberates hydrogen ions or hydronium ions in the electrolytic solution. An acid should be chosen that forms a soluble salt with the metal used in the electrodes.

The electrolyte

The electrolyte is preferably a solution of a salt or other ionizable compound of a metal more noble than hydrogen. It must be ionizable in water and relatively soluble in the mixture of water, the hygroscopic liquid, and the selected acid. By compounding the electrolyte from one or more metals from the same class used in the electrodes, the response characteristics of the electrolyte remain substantially constant for the life of the cartridge. As the anode 22 dissolves, the cathode 24 builds up. The amount and type of electrolyte remain constant, and the number of ions (and therefore the electrical conductivity of the fluid) remains substantially constant over the life of the cartridge.

25
20
15
10
5

Copper sulfate is a suitable salt for the electrolyte. So are other copper salts, such as copper nitrate and copper cyanide. Where silver is the electrode metal, silver nitrate or silver cyanide may be used.

Just as the electrode may be an alloy of copper and silver, for example, so the electrolyte may be a solution of a mixture of salts, such as copper nitrate and silver nitrate.

To prevent the exhaustion of metallic ions from the cathode chamber 15 and the resultant drop in output, a large excess of the electrolytic salt may be provided in the chamber 15 before the diaphragm 31 is sealed to the body 11. Generally, as the ions plate onto and become part of the cathode 24, the concentration of salt in the cathode chamber 15 decreases. At the same time, the dissolving of the anode 22 increases the concentration of salt in the anode chamber 13.

35
30
25
20
15
10
5

One convenient way to assure an excess of the electrolytic salt in the cathode chamber 15 is to pack into it crystals 45 of the electrolytic salt (e. g. copper sulfate crystals). The chambers 13 and 14 and the remaining space in the chamber 15 may then be filled with the fluid 30, which is a solution of the electrolyte in the foundation liquid, and the diaphragm 31 is then sealed in place.

Operation

The terminals 25 and 27 are connected to a source of direct current, so that electrons flow through the fluid 30 from the anode 22 to the cathode 24, via the gaps 20 and 21. Metallic ions leave the anode 22 and disappear in the solution, and metal from the solution is deposited on the cathode 24. This occurs without the formation of gas, because the metallic base of the electrolytic salt and the electrode metal are more noble than hydrogen. The excess salt 45 in the chamber 15 supplies ions to the cathode 24 and prevents an ion deficiency even after prolonged operation. If desired, the terminals 25, 27 may be reversed after a few months of use, and the life of the unit prolonged.

The output voltage is drawn off from the center electrode 23 through the terminal 26, which remains substantially unaffected by the ion transfer going on between the anode and the cathode.

Since the liquid 30 is balanced, its tendency to evaporate substantially equals its hygroscopic

tendencies, so the liquid level will remain substantially constant.

The result of the foregoing discoveries and their application has been to make practical this type of electric pickup and to solve one of the problems which has held back its general use.

What is claimed is:

1. An electrically conductive liquid adapted to be enclosed in an electric control device, comprising a solution of a suitable electrolyte in a mixture of water and a hygroscopic liquid, the evaporative tendency thereof being balanced by its hygroscopicity.

2. The liquid of claim 1 in which there is a small amount of an acid of the type that releases hydronium or hydrogen ions in the liquid and attacks oxides of metals more noble than hydrogen to form a salt soluble in said liquid.

3. A control device for electric circuits, including in combination a body of insulating material having a plurality of chambers therein with successive chambers joined by orifices each having a variable area; means for varying said orifices; and an electrode in each said chamber and having terminal connections outside said body, one said electrode acting as a cathode and another said electrode acting as an anode; an electrolytic liquid in said chambers, said liquid being a saturated solution of an electrolytic compound; and a solid deposit of said electrolytic compound in the chamber whose electrode acts as the cathode, whereby as the metal ions tend to be depleted from the cathode chamber, they are replenished by some of said deposits going into solution, so that the electrical characteristics of said liquid remain constant over a long period of time.

4. A control device for electric circuits, including in combination a body of insulating material having a plurality of chambers therein with successive chambers joined by orifices each having a variable area; means for varying said orifices; an electrode in each said chamber and having terminal connections outside said body; and an electrolytic liquid in said chambers, said liquid being a solution of an electrolyte in a mixture of water and a hygroscopic liquid in such a proportion that the tendency of water to evaporate is balanced by the hygroscopicity.

5. A control device for electric circuits, including in combination a body of insulating material having a plurality of chambers therein with successive chambers joined by orifices each having a variable area; means for varying said orifices; an electrode in each said chamber with terminal connections outside said body; and an

electrolytic liquid in said chambers containing a small proportion of an acid that reacts with the coating that tends to form on the electrode when immersed in the electrolytic liquid, said reaction producing a compound soluble in said liquid, said acid being of the type that liberates hydrogen or hydronium ions in said liquid.

6. A control device for electric circuits, including in combination a body of insulating material having a plurality of chambers therein with successive chambers joined by orifices each having a variable area; an electrolytic liquid in said chambers; an electrode in each said chamber and having terminal connections outside said chamber; means for varying said orifices; and insulated means for protecting said orifice-varying means placed between said orifice varying means and any electrodes that might otherwise come into contact with said orifice-varying means.

7. A control device for electric circuits, including in combination a body of insulating material having a plurality of chambers therein; a flexible diaphragm covering said chambers and helping to provide orifices joining successive chambers; electrolytic fluid in said chambers; electrodes in some of said chambers extending substantially the full height of said chambers so as to expose a large surface area to said fluid; and insulating protective means separating said diaphragm from each said electrode.

8. In an electric control device, means defining at least two enclosures electrically insulated from each other, means defining a liquid path between the enclosures; exterior means for varying the dimensions of said path; means for impressing an electrical potential between said enclosures and through the liquid contained in said path, said liquid comprising a solution of a metal that stands higher than hydrogen in the electromotive series in a mixture of water and a hygroscopic liquid in such proportion that the hygroscopicity balances the water's evaporative tendency.
